US0D1022106S

(12) **United States Design Patent** (10) Patent No.: **US D1,022,106 S**
(45) Date of Patent: ** Apr. 9, 2024

(54) **FIREARM COMPENSATOR**

(71) Applicant: **In Ovation LLC**, Vadnais Heights, MN (US)

(72) Inventor: **Terrence Dwight Bender**, Minneapolis, MN (US)

(73) Assignee: **In Ovation LLC**, Vadnais Heights, MN (US)

(**) Term: **15 Years**

(21) Appl. No.: **29/809,767**

(22) Filed: **Sep. 29, 2021**

(51) LOC (14) Cl. **22-01**

(52) U.S. Cl.

USPC **D22/108**

(57) **CLAIM**

The ornamental design for a firearm compensator, as shown and described.

DESCRIPTION

FIG. 1 is a front angled view of the firearm compensator. FIG. 2 is a back angled view of the firearm compensator. FIG. 3 is a front view of the firearm compensator. FIG. 4 is a back view of the firearm compensator. FIG. 5 is a top view of the firearm compensator. FIG. 6 is a bottom view of the firearm compensator. FIG. 7 is a right side view of the firearm compensator; and, FIG. 8 is a left side view of the firearm compensator. The broken lines in the drawings disclose unclaimed portions of the firearm compensator only and form no part of the claimed design.

1 Claim, 4 Drawing Sheets
